UNITED STATES PATENT OFFICE.

CHARLES J. KNAPP, OF NEW YORK, N. Y.

IMPROVEMENT IN LAMP-EXTINGUISHERS.

Specification forming part of Letters Patent No. 172,035, dated January 11, 1876; application filed December 4, 1875.

To all whom it may concern:

Be it known that I, CHARLES J. KNAPP, of the city, county, and State of New York, have invented a new and Improved Lamp-Extinguisher, of which the following is a specification:

Figure 1 represents a side elevation of a burner with my improved extinguishing device; and Fig. 2 is a vertical transverse section, and Fig. 3 a top view, of the same.

Similar letters of reference indicate corresponding parts.

My invention relates to a simple, reliable, and effective extinguishing device for lamp-burners, that may be easily handled so as to extinguish the flame in an instant.

My invention consists of posts or standards, which are applied to the narrow sides of the wick-tube, and provided at the upper ends with pivoted caps that are operated to close over the wick-tube, or opened by a forked and weighted or spring-acted lever with cap-connecting links.

In the drawing, A represents a lamp-burner of any suitable construction; B, the wick-tube, and C the posts or standards that are secured to the narrow sides of the same, running up to nearly the same height therewith. Two caps, D, are pivoted symmetrically at both sides of the wick-tube to the upper ends of the posts, and connected by hinged butts a to the forked ends b of a weighted or spring-acted lever-handle, E, that is fulcrumed to the base-plate of the lamp-burner, and extended to some distance beyond the outer periphery of the same. The forked ends b of the lever are parallel to the wick-tube, and engage, by their hook-bent

ends, the eyes of the cap-connecting links, so as to slide readily therein when the lever-handle is operated, and cause the opening and closing of the caps. The weight or spring of the fulcrumed lever-handle serves to secure the automatical opening of the caps after the same have been closed by depressing the lever. The caps close above the wick-tube, and extinguish instantly the flame in a perfectly reliable manner.

In place of the links and forked lever-handle for operating the caps, any other equivalent device for swinging the caps on the posts may be used, as I do not confine myself to the special construction described.

I am aware that caps closing over the flame of a candle or lamp to extinguish the same have been used heretofore, and I therefore do not claim the same broadly; but I claim the pivoting of the caps to side posts of the wick-tube, as thereby a strong support to the caps is given, and the regular and effective working of the same obtained, they being not affected by the influence of the heat, or worked by springs that soon get out of order and useless.

Having thus described my invention, I claim as new and desire to secure by Letters Patent—

The caps D, pivoted on each side of wick-tube to the upper ends of posts C, and connected by hinged links a with ends of an automatically-opening lever, as and for the purpose specified.

CHARLES J. KNAPP.
